UNITED STATES PATENT OFFICE.

GEORGE W. LUCKENBAUGH, OF BRADFORD, OHIO.

END-GATE.

1,244,351.

Specification of Letters Patent. Patented Oct. 23, 1917.

Application filed February 27, 1917. Serial No. 151,316.

To all whom it may concern:

Be it known that I, GEORGE W. LUCKENBAUGH, a citizen of the United States, residing at Bradford, in the county of Miami and

5 State of Ohio, have invented new and useful Improvements in End-Gates, of which the following is a specification.

This invention comprehends the provision of an end gate for wagons, embodying two 10 sections, one of which is capable of sliding adjustment across the other section, to permit the end gate to be easily and quickly arranged between the guides therefor at the opposite sides of the wagon body, and re- 15 moved from the latter without lifting the end gate vertically.

The nature and advantages of the invention will be readily apparent from the following detail description taken in connection with the accompanying drawing, the 20 invention residing in the construction, combination and arrangement of parts as claimed.

In the drawing forming part of this 25 specification like numerals of reference indicate similar parts in the several views and wherein:—

Figure 1 is a fragmentary view of a 30 wagon body showing my improved end gate operatively associated therewith.

Fig. 2 is a sectional view taken through the end gate, showing the movable section in its retracted position.

Fig. 3 is a sectional view taken on line 35 3—3 of Fig. 2.

The end gate constructed in accordance with my invention preferably embodies two sections 10 and 11 respectively, which are disposed in overlapping relation, with means 40 for adjusting the section 10 across the section 11, with a view of increasing or decreasing the length of the gate for the purpose to be presently stated. As shown in

Fig. 1 the end gate is associated with the 45 wagon body in the usual well known manner, a pair of spaced cleats 12 being secured to each side of the wagon body, and between said cleats the end gate is fitted and held in proper position upon the wagon

50 body. Manifestly when the section 10 is adjusted in a direction to decrease the length of the gate, the same can be placed upon the wagon body, with the section 11 fitted between its respective guide cleats 12. The

55 section 10 may then be subsequently adjust-

ed to increase the length of the end gate, whereupon the section 10 is moved between its respective guide cleats at the opposite side of the wagon.

A pair of endless bands 13 embrace the 60 respective sections of the gate at spaced intervals, and in addition to serving as guides for the movable section 10, the bands further assist in holding the respective sections operatively associated. Bolts 14 are passed 65 through the bands and the respective sections, whereby the bands are fixed relatively to the gate, but the section 10 is provided with an elongated slot 15 for each bolt, to provide for the relative sliding adjustment 70 of this section as above stated. Pivoted upon the section 11 adjacent one end thereof is an operating lever 16, which is connected with the movable section 10 through the instrumentality of an extension 17. Ob- 75 viously when the lever 16 is adjusted in one direction the section 10 is moved in a direction to decrease the length of the gate, and when the lever is adjusted in an opposite direction the section 10 assumes the position 80 whereby the length of the gate is increased. It will be noted that by reason of this construction and contemplated operation, the end gate can be quickly and easily placed in position upon the wagon body, and just 85 as easily removed therefrom without necessitating lifting of the gate vertically.

While it is believed that from the foregoing description the nature and advantages of the invention will be readily apparent, I 90 desire to have it understood that I do not limit myself to the precise construction shown, as the same is merely illustrative of the preferred embodiment of the invention, and that such changes may be resorted to 95 when desired as fall within the scope of what is claimed.

What is claimed is:—

An end gate comprising a pair of overlapping sections, one of said sections having 100 elongated slots, endless bands embracing said sections, bolts for securing the bands to the end gate and passed through said slots of one section for permitting the latter a sliding adjustment with respect to the other 105 section to increase or decrease the length of the gate, and means for adjusting said movable section.

In testimony whereof I affix my signature.

GEORGE W. LUCKENBAUGH.
